MAGNETIC NAIL HOLDER OR THE LIKE

Cloyd D. Smith, 13805 Rancheros Drive,
Reno, Nev. 89502

Filed July 12, 1966, Ser. No. 3,046

Term of patent 14 years

(Cl. D54—13)

FIG. 1.

FIG. 2.

FIG. 3.

FIG. 5.

FIG. 4.

FIG. 6.

FIGURE 5 is a front end elevational view, showing in dotted lines a brad as it might be held in the holder jaws for illustrative purposes only; and

I claim:

The ornamental design for a magnetic nail holder or the like, as shown and described.
